MURDICK F. MURPHY AND COLIGNEY BRAINERD METHENY, OF BEAVER FALLS, PENNSYLVANIA, ASSIGNORS TO STERLING PHOTO MANUFACTURING CO., OF BEAVER FALLS, PENNSYLVANIA, A CORPORATION OF PENNSYLVANIA

FILM-DEVELOPING TANK

Application filed June 19, 1931. Serial No. 545,386.

The invention relates to the development of photographic films and plates. The development of such films comprises the steps of immersing the films in a developing solution, then washing them in a rinsing liquid, and next immersing them in a "fixing" solution, and, finally, washing them in the rinsing liquid. The composition of the different liquids employed in such process is not of immediate concern in our invention. Neither are we concerned with the number of baths, nor the particular sequence of steps which is followed in developing the films. We are, however, concerned with the container for the several liquids necessary in film development, and it is in such a container—a container commonly known in the art as a developing tank—that our invention is found.

Large X-ray films and other large photographic films are usually secured to hangers, hangers being devices of well-known structure to facilitate handling the films and to maintain them in flat condition during the developing operation.

The object of our invention is to provide a compartmented tank for containing two or more baths of the liquids required for film development—a tank which is of particular utility where hangers are employed, as above-mentioned.

The rinsing of films is ordinarily done in a circulating bath of water, and a further object of our invention is to provide a developing tank in which a developing solution is maintained in one compartment, and in which a particularly effective bath of rinsing liquid is maintained in another compartment. That is, we have in mind the provision of a structure which will admit of a maximum circulation of rinsing water, under the usual conditions of water supply. Another object is to provide a tank structure in which the hangers, as well as the films, may be wholly submerged in the rinsing bath, to the end that they shall be cleansed thoroughly.

A still further object of our invention is to provide an integrally formed tank (that is, a tank of monolithic structure) which can be readily formed of ceramic material, and which can be easily cleaned when taken from

service. Other objects will be apparent in the following specification.

In the accompanying drawing Fig. I is a view in plan from above of a tank embodying our invention; Fig II is a view of the tank in side elevation; Fig. III is a view of the tank in cross section, taken on the plane III—III of Fig. II; Fig. IV is another view of the tank in cross section, taken on the plane IV—IV of Fig. II; and Fig. V is a fragmentary view, showing an elaboration in detail.

Referring to the drawing the tank in this case is shown to be a tank comprising a substantially rectangular outer wall 1, a bottom 8, and partition walls 3. Three compartments A, B, and C are provided in the illustrated tank; the compartment A advantageously contains a bath of developing solution; the compartment B contains the rinsing bath; and in compartment C the "fixing" solution is contained. On the outer wall 1 of the tank there is located a conduit 4; the conduit is integral with the wall of the tank; its upper end terminates adjacent the top of the compartment (B) for the rinsing liquid, and the wall of such compartment is so particularly formed as to provide a lip 5 over which the rinsing liquid may spill into the conduit 4. More will presently be said as to the utility and organization of the lip 5.

An inlet 6 is provided adjacent the bottom of compartment B, and by means of a suitable connection to a supply pipe, water is introduced under pressure. Accordingly, water being introduced continuously, the surface of the rinsing bath in compartment B (as indicated by the line S in Fig. IV) rises above the lip 5. Water overflows the lip and falls through the conduit 4, which conduit is provided at its lower end with an outlet 7. The outlet 7, manifestly, may be connected to any convenient drainage or sewerage system. The above-described organization of the inlet and the overflow discharge for the circulating bath of rinsing water is such that a maximum movement of water may be obtained in a compartment of given dimensions. In each partition wall 3, advantageously at a point flush with the face of floor

2, is a port 8, while through the wall 1 of compartment B is a drainage vent 9. The ports 8, 8 and vent 9 are adapted to be closed, say by means of stoppers, such as the stopper 5 10 illustrated in Fig. I.

When the tank is in service, that is, when the compartments contain their film-developing baths, the ports 8, 8 and vent 9 are closed. When, however, it becomes expedient to re- 10 place the solutions in compartments A and C, the stoppers are withdrawn from the ports 8, 8, 9, and the supply of water to inlet 6 is cut off. Thereupon the contents of all compartments quickly flow into the conduit 4, 15 and thence to the drain pipe (not shown) which is, as above-mentioned, connected to outlet 7.

It will be noted that the structure of the tank is such that the walls, the partitions, and 20 the conduit 4 may be formed integrally. Indeed, we form the tank integrally of vitreous china, and remark that one of our prime concerns was to provide a structure which would have the above-mentioned advantages, 25 and which could be manufactured, as a unitary thing, of ceramic material. Advantageously, the walls 1 of the tank are tapered downward, as indicated at T in Figs. II and III; such tapering of the walls facilitates 30 molding the structure from so-called green clay or like material. Additionally, the structure is such that all surfaces of it may be cleansed thoroughly. It is remarkable that in tanks employed hitherto the conduits, 35 for the overflow of the circulating bath of rinsing liquid, have comprised metal pipes. A metal pipe, in being connected to the rinsing bath container, afforded a circular opening (i. e. the circular bore of the pipe) for 40 the escape of rinsing liquid, and, as in service such metal conduit corroded and became clogged, as in fact it has been found to do, the conduit had to be renewed, or if not renewed, it had to be cleaned. Manifestly, 45 cleaning the bore of a corroded pipe is a difficult task, while the renewal of the pipe involves expense. By forming our conduit (4) integrally on the wall of the tank, and by forming it of the shape illustrated and of the 50 material specified, we have provided a structure which is readily accessible for cleaning, and one which may be thoroughly cleansed. Furthermore, it is a structure wherein the 55 discharge of overflowing cleansing liquid is practically unrestricted. That is, the overflow lip 5 admits of much greater discharge of liquid from compartment B than could be obtained by employing the usual metal conduit, it being obvious that a metal pipe (due 60 to its circular area) cannot receive or conduct the amount of fluid that the conduit 4, with its wide overflow lip 5, can handle.

Another feature is found in our tank. As 65 above mentioned, hangers are employed to

maintain the films in flat condition, and to facilitate handling them in the developing operation. In the drawing, we have illustrated in outline two hangers H and H'. The specific structure of these hangers is a matter of common knowledge, and we shall not concern ourselves with them, further than to mention that they comprise a rectangular frame having two ears h on the upper leg L of the frame, to the end that the hangers may be suspended, as indicated in Figs. III and IV. The walls of each compartment of the tank are so particularly formed as to provide opposite ledges or edges a—a, b—b, and c—c, cf. Fig. I. The opposed edges in each compartment are adapted to support the hangers H by their ears h, and it is characteristic of our structure that the hanger-supporting edges of the solution-containing compartments (in this case the compartments A and C) are offset vertically from the edges b—b of the rinsing compartment B. Such relative, vertical disposition of the hanger-supporting edges a—a, b—b, and c—c is important to the end that, when the hangers are suspended in the solution-containing compartments, their upper legs L shall lie above the surface of the developing solution. This will, as is desirable, keep the legs L substantially free of the developing solution. The hanger-supporting edges b—b are lower than the hanger-supporting edges of compartment A and C; the edges b—b are so vertically disposed with respect to the overflow lip 5 as to permit the legs L of the hangers to lie beneath the surface S of the rinsing bath. Accordingly, the entire hanger is submerged in the cleansing bath, and any solution adhering to any part of the hanger will be removed in the rinsing bath, and streaking of the films, by reason of fouled hangers, will be prevented.

It will be observed that one edge b provides in addition to a support for hangers, the lip, over which the rinsing liquid is adapted to spill. If, in a particular installation, the supply of water entering inlet 6 is insufficient to maintain the surface S of the rinsing bath the desired interval above the lip 5, to insure that the legs L of the hangers will be submerged, we contemplate providing a ridge b' on the hanger-supporting edge b, lying adjacent the conduit 4. This detail is illustrated in Fig. V, where it will be manifest that the ridge b' may be integrally included with the tank structure, as it is shown to be, or it may comprise a separate bar that can be secured on the edge b in any convenient manner.

We claim as our invention:

1. A developing tank including a compartment for a bath of film-developing solution and a compartment for a circulating bath of rinsing liquid, each compartment being provided with opposed

- edges for the support of film hangers, and an outlet conduit on the wall of said tank, which outlet conduit at its upper end terminates adjacent the top of the rinsing compartment, said rinsing compartment having an inlet for the introduction of rinsing liquid adjacent the bottom of the compartment, and a lip adjacent its top for the overflow of rinsing liquid into said conduit. 5
10. 2. A developing tank including a compartment for a bath of film-developing solution and a compartment for a circulating bath of rinsing liquid, each compartment being provided with opposed edges for the support of 15 film hangers, the hanger-supporting edges of said rinsing compartment being offset vertically from the supporting edges of said solution compartment, an outlet conduit on the wall of said tank, which outlet conduit at its 20 upper end terminates adjacent the top of the rinsing compartment, said rinsing compartment having an inlet for the introduction of rinsing liquid adjacent the bottom of the compartment, and a lip adjacent its top for 25 the overflow of rinsing liquid into said conduit.
11. 3. A developing tank comprising an integrally formed or monolithic body which includes a compartment for a bath of film-developing solution and a compartment for a circulating bath of rinsing liquid, each compartment having on its opposed walls edges for the support of film hangers, the supporting edges in said rinsing compartment being offset vertically from the supporting edges of said solution compartment, an outlet conduit formed on the wall of said tank, which outlet conduit at its upper end terminates adjacent the top of the rinsing compartment, 35 which rinsing compartment includes in its wall a lip for the overflow of rinsing liquid into said conduit.
12. 4. A developing tank including a compartment for a bath of film-developing solution and a compartment for a circulating bath of rinsing liquid, each compartment being provided with opposed edges for the support of film hangers, an outlet conduit on the wall of said tank, which outlet conduit at its upper 45 end terminates adjacent the top of the rinsing compartment, said rinsing compartment having an inlet for the introduction of rinsing liquid adjacent the bottom of said compartment, and a lip adjacent its top for the overflow of rinsing liquid into said conduit, together with a drainage vent at the bottom of said rinsing compartment communicating with said conduit. 55
13. 5. The structure of claim 4, in which a port is provided between said compartments, which port, together with the above-mentioned drainage vent, is adapted to be closed when the tank is in service. 60
14. 6. A developing tank comprising an integrally formed or monolithic body which in- 65
- cludes at least two liquid-containing compartments, the walls of each compartment being formed for the support of film hangers, an outlet conduit formed on the wall of said tank, which outlet conduit at its upper end terminates adjacent the top of one of said compartments, and the last-mentioned compartment being provided with a lip in its wall for the overflow of liquid into said conduit. 70
7. A developing tank comprising an integrally formed or monolithic body which includes at least two compartments, one compartment for a bath of film-developing solution, and another compartment for a circulating bath of rinsing liquid each compartment having, on its opposed walls, edges for the support of film hangers, an outlet conduit formed on the wall of said tank, which outlet conduit at its upper end terminates adjacent the top of the compartment for said rinsing liquid, which last-mentioned compartment includes in its wall a lip for the overflow of rinsing liquid into said conduit, and also includes an inlet for the introduction of liquid adjacent the bottom of the compartment, a drainage vent adjacent the bottom of said rinsing compartment communicating with said conduit, a port extending through the wall of adjoining compartments, which port, together with the above-mentioned drainage vent, is adapted to be closed when the tank is in service. 80
8. A developing tank comprising an integrally formed or monolithic body including at least two compartments, one of such compartments being adapted to contain a circulating bath of water, edges on the opposed walls of said last-mentioned compartment for the support of film hangers, an inlet for the introduction of water adjacent the bottom of said compartment, an outlet conduit on the wall of said compartment, which outlet conduit at its upper end terminates adjacent the top of said compartment and is open adjacent one of said hanger-supporting edges, whereby said edge comprises an overflow lip for said bath of water. 100
15. In testimony whereof we have hereunto set our hands.
